Inventor

William C. Hunter.

United States Patent Office.

WILLIAM C. HUNTER, OF NEWPORT, KENTUCKY.

Letters Patent No. 75,762, dated March 24, 1868.

IMPROVED WASHING-MACHINE.

The Schedule referred to in these Letters Patent and making part of the same.

TO ALL WHOM IT MAY CONCERN:

Be it known that I, WILLIAM C. HUNTER, of Newport, in the county of Campbell, and State of Kentucky, have invented a new and useful Improvement in Washing-Machines, of which the following is a full and clear description, reference being had to the accompanying drawings, making part of this specification.

The nature of my improvement in washing machines consists in the arrangement within the body of the machine of two series of rollers, one series being located immediately above the concave bottom, and the other series pivoted to either end of the machine, radiating downwards; also to a vibrating finger-bar pivoted in the lid, and operated by a lever hinged to the outer face of the machine.

Figure 1 is a perspective view of the washing-machine.

Figure 2 is a transverse section of the same.

Figure 3 is a perspective view of the vibrating "finger-bar."

A is the body of the washing-machine, provided with the circular bottom *a*. The ends *b* of the machine are plane surfaces, perpendicular to the curved bottom *a*. The lid A' is hinged to the front of the body A. It is perforated in the centre for the reception of the cylindrical box B, which has axial arms journalled in the lid A'. The cylindrical box B is constructed with a diametrical opening, in which the arm C of the vibrating finger-bar D is adjusted, and secured in place by the pin *c*. Said pin *c* passes through perforations in the cylindrical box, B, and arm C. A cross-head E is secured to the arm C within the body A of the machine. It is provided with a number of fingers, E', which project downward. The two fingers at each end of the cross-head E' diverge to the front and rear, not being in the plane of the central fingers. The external end, *c'*, of the arm C is pivoted to the connecting-rod G, and the opposite end of the rod G is pivoted to the lever H. The lever H is pivoted to the front end of the body of the machine at *d*. Immediately above the bottom, *a*, of the body A, are the rollers I, journalled in the ends *b* of the machine. Series of radiating rollers, K, placed near and parallel to the ends *a* of the machine, are so journalled that they rotate freely, as do the rollers in the bottom of the machine.

Operation.

The requisite amount of water having been placed in the body A of the machine, and the clothes to be washed, the lid A' is closed and secured in place. When the bulk of clothes to be operated upon is great, the arm C of the vibrating finger-bar D is drawn up through the opening in the cylindrical box B to such a height that the fingers E' E' shall be caused to engage the articles being washed without pressing them down upon the rollers I with too much force to impede the easy operation of washing, which is accomplished by the operator, who grasps the free end of the lever H, moving back and forth. The clothes under the fingers E' E' are pressed over and upon the rollers as they are moved to and fro, and are worked upon in a manner similar to that undergone when the hands are used in place of the fingers E' E'. The radiating rollers K, while they prevent the bunching up of the clothes at each end of the machine, serve the same purpose in the operation of washing as do the rollers I.

What I claim as new, and desire to secure by Letters Patent, is—

The rollers I and K, the vibrating finger-bar D, having the cross-head E, and fingers E' E', the cylindrical box B, pin C, and connecting-rod G, and lever H, when the same are constructed and arranged substantially as herein described and for the purpose specified.
